UNITED STATES PATENT OFFICE

ROLAND C. PRIEST, OF WHITTENBURG, TEXAS, ASSIGNOR OF ONE-FOURTH TO LEWIS P. UHREY, ONE-FOURTH TO GUSTA W. UHREY, AND ONE-FOURTH TO JOHN W. SANDERSON, ALL OF WHITTENBURG, TEXAS

FLUE RECONDITIONING APPARATUS

Application filed August 1, 1928. Serial No. 296,834.

My invention relates to tools for reconditioning used flues and more particularly to a combination machine for cleaning, cutting and rolling flues, the principal object of this invention being to reclaim used flues for further service by removing the collected scale from their outer surfaces, by cutting off ragged ends providing new squared end faces for the flues, and by rolling these ends into bell-shaped form for correct mounting in boilers or the like.

A further object is to provide such a machine in a single unit to expedite the several operations necessary for reclaiming a used flue.

A further object of the invention is to provide shifting means for the scaling operation to reverse the travel of the flue through this process, should a single operation fail to satisfactorily clean the flue.

In accomplishing these and other objects of the invention I have provided improved details of structure, the preferred forms of which are illustrated in the accompanying drawings, wherein:

Fig. 1 is a perspective view of a machine embodying my invention, illustrating the rolling operation for forming a bell mouth on the end of a flue.

Fig. 2 is a similar perspective view particularly illustrating the scaling operation.

Fig. 3 is a central vertical sectional view of the machine.

Fig. 4 is a cross sectional view on the line 4—4, Fig. 3.

Fig. 5 is a cross sectional view on the line 5—5, Fig. 3.

Referring more in detail to the drawings:

1 designates a supporting frame, preferably constructed of angle irons joined together by welding and including lower end members 2, side members 3 and an intermediate channel bar 4 secured to the side members. Mounted at each corner of the frame and at substantially central points on the side members 3 are vertical posts 5, upper end members 6 and 7, side members 8, and an intermediate cross bar 9 being fixed to the upper ends of the posts. The frame con-

structed and assembled as above described may be mounted on cross sills, such as 10.

Journaled in bearings 11 mounted on the upper end and cross members 6, 7 and 9 is a main shaft 12 restrained from longitudinal movement by collars 13 fixed to the shaft, a spur gear 14 being keyed to the shaft near the outer face of the end member 7.

Supported in pairs of bearings 15 and 16 secured to the lower faces of the cross member 7 and end member 8 are shafts 17 and 18 carrying complementary cleaning rollers 19 and 20, driving gears 21 and 22 keyed to the outer ends of the shafts meshing with the spur gear 14. The cleaning rollers are provided with oppositely screw-threaded surfaces 23 and 24 having tapered outer ends for a purpose presently described.

A bearing 25 fixed to the channel bar 4 rotatably supports the stub shaft 26 of a feed mechanism 27 including spaced parallel side plates 28 fixed to the shaft 26 and between which are mounted feed rollers 29. Pivotally attached to the shaft 26 is a lever 30 adapted to be operated over a fulcrum 31 welded to the bar 4. As indicated by the dotted lines in Fig. 4, a flue is held in engagement with the threaded cleaning rollers by the feed rollers 29, pressure on the lever 30 over the fulcrum 31 increasing the frictional contact between the flue and cleaning rollers.

Because of the tapered ends on the cleaning rollers a rotary movement of the feed unit causes a positive contact of the flue with the cleaning rollers and lateral shifting of the lever 30 in one direction causes a greater pressure contact between one of the feed rollers 29 and one of the cleaning rollers and pressing the flue against the tapered portion of said cleaning roller.

Since the screw threads on these rollers are cut in opposite directions and the rollers rotate in the same direction, the direction of feeding travel imparted to the flue is thus determined by shifting the lever 30 whereby a greater extent of one roller is engaged with the flue.

Mounted on a threaded reduced end 32 of the main shaft 12 is a cutting disk 33 secured to the shaft by a washer 34 and nut 100

35 and comprising a part of the cutting mechanism now to be described.

An upwardly extending arm 36 fixed to an upper corner of the cutting end of the frame 5 pivotally supports a pair of spaced parallel side plates 37, rotatably supporting between them on bolts 38 a pair of feed rollers 39 comprising bearings for retaining the flue when the flue is pressed against the cutter and being rotated by the flue when the latter is rotated by the cutter.

A toggle connection for raising and lowering the feed rollers and supporting plates includes a pair of links 40 pivotally supporting near their upper ends, as by a bolt 41, the free ends of the side plates 37.

Secured to the top of the frame oppositely from the arm 36 are upwardly extending ears 42 spaced complementary to the spacing between the links. Supported between the ears on a pivot pin 43 is a lever 44 also pivotally connected to the lower ends of the links by a bolt 45. A U-shaped hanger 46 for supporting a flue is attached to the outer side plate 37 by the bolts 38. Extending from the inner wall of the arm 36 is an ear 47 carrying one end of a shaft 48, the other end of the shaft being supported in a bridge 49 fixed to the frame above and parallel to 30 the cross bar 9.

Slidably mounted on the shaft 48 is a gauge 50 including a bearing portion 51 pivoted on the shaft and integral with a bar 52 having a depending downwardly extending finger 53 for normally resting on the upper edge of the frame. When one end of a flue is inserted between the cutting disk 33 and feed rollers 39, it abuts against the bar or gauge 52, a stop collar 54 adjustably 35 mounted on the shaft 48 determining the position of the gauge and relative length of the portion cut off the flue. When the cutting operation has been completed, the gauge may be swung on the shaft out of the way 40 for other operations.

Extending above and parallel to the cross member 7 are brackets 55 inclining toward each other and provided with vertical portions 56 for pivotally receiving between them 50 the outer end of a shaft 57 hinged on a bolt 58. The bridge 49 is provided with upstanding spaced ears 59 between which is pivotally mounted, on a bolt 60, a lever 61 having an integral depending tongue 62 carrying 55 the inner end of the shaft 57. A flue-receiving roller 63 is rotatably mounted on the extreme end of the shaft 57 and held in place by a nut 64 threaded on the shaft. Fixed to the upper edge of the bridge is a socket 65 for receiving a spring 66 which normally urges the lever and supported shaft and roller in a raised position to space the flue receiving roller 63 from an aligning forming roller 67 keyed to the main shaft 12, the shaft 60

being driven through a pulley 68 from any suitable power source.

To clean and repair flues with a machine constructed and assembled as above described, a flue, having an outer coating of rust and scale, is inserted between the cleaning and feed rollers. Downward pressure on the lever 30 over the fulcrum 31 brings the flue into contact with the cleaning rollers, which are driven through the gears 14, 21 and 22. The screw threads on the rollers being arranged oppositely to each other, remove the coating of scale from the flue, and simultaneously propel the flue through the machine, the direction of propulsion being determined by the roller having the greater amount of contact with the flue due to lateral pressure on the lever 30.

After being cleaned the flue is inserted between the cutting disk and its complementary feed rollers until its end abuts against the gauge bar 52, the rollers being urged downwardly by the toggle links and lever 44. Continued rotation of the cutting disk through the pulley 68 and extreme pressure of the feed rollers obtained through the toggle connection of the lever quickly cuts the flue at the desired point. As illustrated in Fig. 1, the toggle lever, when not in use, rests in an upward inclined position to permit the use of the U clamp attached to the feed mechanism for the last operation, or the rolling of the flue ends, the gauge bar being also swung on its bearing to avoid interference with this operation.

To bell the ends of the flue for reseating in the boiler heads, the flue is inserted in the U-shaped clamp and its end passed in an upwardly inclined position above the roller 67 and over the roller 63. Downward pressure on the lever 61 causes an angular contact between the flue end and forming roller 67 driven through the main shaft 12, and in turn rotating the flue and its receiving roller through frictional contact. The rolling process is continued until a satisfactory bell-mouth has been formed on the flue and it is then ready for further service.

If the flues conditioned as described are to be reused in the same boiler from which they were removed, their original length may be restored by welding sections of the same diameter to the ends thereof before belling.

What I claim and desire to secure by Letters Patent is:

1. In apparatus of the class described, a support, a drive shaft mounted in the support, cleaning means actuated by the drive shaft for cleaning the surfaces of flues, cutting means on the shaft, and rolling and forming means operable by the shaft including a forming roller mounted on the shaft and a flue receiving roller pivotally mounted in alignment with the forming roller.

2. In apparatus of the class described, a support, a drive shaft mounted in the support, cleaning means actuated by the drive shaft for cleaning the surfaces of flues, including tapered cleaning rollers having oppositely threaded outer surfaces and pressure means for forcing a flue against the rollers, flue cutting means on the shaft, and means operable by the shaft for rolling and forming the ends of a flue.
- 10 3. In apparatus of the class described, a support, a drive shaft mounted in the support, cleaning means actuated by the drive shaft for cleaning the surfaces of flues, including tapered cleaning rollers having oppositely threaded outer surfaces and pressure means for forcing a flue against the rollers including pressure rollers pivotally mounted in both linear and lateral relation to the cleaning rollers, means on the shaft for cutting flues, and means operable by the shaft for rolling and forming flues.
- 15 4. In apparatus of the class described, a support, a drive shaft mounted in the support, cleaning means actuated by the drive shaft for cleaning the surfaces of flues, cutting means on the shaft, and rolling and forming means operable by the shaft including a forming roller mounted on the shaft, a flue
- 20 receiving roller shaft and roller pivotally mounted in alignment with the forming roller, and a lever carrying the free end of the roller shaft for exerting pressure on the flue-receiving roller.
- 25 5. In combination with a flue conditioning mechanism including a supporting frame, a shaft rotatably mounted on the supporting frame, a cutter on the shaft, a forming roller on the shaft, flue supporting means associated with the cutter and the forming roller, and means for moving the flue into forming relation with the forming roller.
- 30 6. In apparatus of the character described including a support, and a shaft mounted on the support, means actuated by said shaft for cleaning the surface of a flue, cutting means on the shaft, forming a roller mounted on said shaft, means on the support associated with the cutting means and said forming roller for retaining the flue, and means for moving the flue into forming relation with the forming roller.
- 35 In testimony whereof I affix my signature.
ROLAND C. PRIEST,
